ARTICLE LIFTING APPARATUS

Herman Jacquot, Pittsburgh, Pa., assignor to Jones & Laughlin Steel Corporation, Pittsburgh, Pa., a corporation of Pennsylvania

Application August 4, 1954, Serial No. 447,828

6 Claims. (Cl. 294—86)

This invention relates to apparatus for lifting elongated articles and is more particularly concerned with such an apparatus for lifting piles of such articles into and out of confined spaces.

Heavy elongated articles, such as steel blooms and billets, bars, beams, pipe and the like are generally handled by crane because of their weight. The conventional method of lifting such articles either singly or in piles is to employ a pair of slings which are wrapped around the articles and attached to the crane hook. These slings, which may be made of rope or chain, must be passed under the article and attached to the crane hook manually. Each crane which must lift such articles usually requires not only an operator in the cab but also a man on the ground, called a crane follower, to attach and detach the slings above mentioned. When loads of such articles are to be removed from gondola cars or other confined spaces, the crane follower frequently is required to clamber up over the load in order to pass the slings around it, which slows down such unloading and increases its difficulty.

It is an object of my invention, therefore, to provide apparatus which may be carried by a crane and is capable of engaging and lifting elongated articles automatically, so dispensing with a crane follower. It is another object of my invention to provide such apparatus which requires a minimum of side clearance around the load and so may be used in gondola cars and other confined spaces. Other objects of my invention will appear in the course of the following description and explanation.

A present preferred embodiment of my invention is illustrated in the attached figures to which reference is now made.

Figure 1 is a side elevation of such an embodiment with its load engaging members in open position.

Figure 2 is an end elevation of the apparatus shown in Figure 1.

Figure 3 is an end elevation of the apparatus of my invention, unsupported, in which the load engaging members are in closed position.

Figure 4 is a plan of a portion of the apparatus of Figure 1 viewed from below.

Figure 5 is a perspective of a portion of my apparatus in which certain elements are broken away to provide a clearer view of operating parts.

Figure 6 is a detail view partly in section of a latch element of my apparatus which acts automatically to connect and disconnect portions thereof.

Figure 7 is a perspective showing part of the element of Figure 6 and other portions of my apparatus in disconnecting relation.

Figure 8 is a view similar to that of Figure 7 with the parts shown in connecting relation.

Figure 9 is an exploded view of a portion of my apparatus as shown in Figure 1.

My apparatus is provided with a massive upright load transmitting member 1 formed with an aperture 2 at

2

its upper end adapted to fit over a crane hook. Load transmitting member 1 is also formed with a pair of vertical parallel slots 3 and 4 which extend over a portion of its length. The bottom of member 1 is provided

5 with a central cutout 6, shown in Figure 9, to accommodate a latch element to be described. Massive cross pieces 7 and 8 are bolted across member 1 at the bottom thereof and may be spaced from member 1 by spacer plates 9—9. A cross member designated generally 14 is formed by heavy rectangular members 10 and 11 spaced apart to admit two pairs of hanger elements 12—12 and 13—13, one pair at either end. These hanger elements 12—12 and 13—13 are cut out or mortised on each side as shown so as to align members 10 and 11 with each other and to fit over these members, but are not directly attached to members 10 and 11. Members 10 and 11 are further spaced apart by thin rectangular members 15 and 16 respectively, which are provided with rectangular cutouts 17 and 18 respectively 10 in the center of their lower edges further to enlarge the opening 6 which accommodates the latching element to be described. Members 10 and 11 are held together by shoulder cross bolts 20—20 and 21—21 which are positioned to pass through slots 4 and 3 respectively of load transmitting member 1. Member 1 is thus slideably connected to the cross member 14. Load is transmitted from cross member 14 to upright member 1 through cross pieces 7 and 8.

A second cross member designated generally 23 has a flat bottom plate 24 to which is attached at one end a pair of spaced upstanding lugs 25—25 and at the other end a similar pair of spaced upstanding lugs 26—26. Between spaced lugs 25 is positioned a lug 28 having an elongated vertical extension 29 and between lugs 26 is positioned an upstanding lug 30 having an elongated vertical extension 31. Vertical extension 29 is positioned to pass upwardly between horizontal members 10 and 11 in the space between the pair of hangers 12—12 previously mentioned, and vertical extension 31 is likewise positioned to pass upwardly between horizontal members 10 and 11 in the space between hangers 13—13. Cross members 14 and 23 are maintained parallel to each other by the construction above described, but can move toward and away from each other as vertical extensions 29 and 31 slide between hangers 12—12 and 13—13 respectively.

A pair of pins 33—33 pass through lugs 25—25 and 28, a similar pair of pins 34 pass through lugs 26—26 and 30. Over pins 33—33 in the spaces between lugs 25—25 and 28 are positioned rollers 36—36. Similar rollers not shown are similarly positioned on pins 34—34. An elongated arcuate tong member 38 provided with an elongated arcuate slot 39 is mounted between lugs 25 and 28 so that pins 33 and rollers 36 pass through slot 39. A second opposed elongated arcuate tong member 40 provided also with an elongated arcuate slot 41 is similarly mounted between lugs 25 and 28, on the other side of lug 28 from tong member 38. The other end 55 of cross member 23 is provided with a like pair of elongated arcuate tong members 42 and 44 respectively. All tong members are of the same length and extend around an arc of more than 180°.

The upper end of tong member 38 is pivotally connected by pin 46 between a pair of links 47—47. The upper ends of links 47—47 are pivotally connected by pin 48 to the lower ends of hanger elements 12—12. The upper end of tong member 40 is likewise pivotally connected by pin 50 to a pair of links 51—51, the upper ends of which are also pivotally connected by pin 53 to lower ends of hanger elements 12—12. Tong members 42 and 44 are likewise connected to the lower ends

of hanger elements 13—13 by pairs of links 55—55 and 56—56 respectively.

Cross member 23 is provided with a pair of plates 59—59 positioned above plate 24 and spaced apart to form centrally located slot 60 positioned with its long axis at right angles to the long axis of cross member 23.

In the cutout opening 6 at the lower end of load transmitting element 1 is mounted a latch mechanism designated generally 61 and shown in Figure 6. This latch is provided with a cylindrical plunger element 62 mounted vertically within a cylindrical cavity 63. Element 62 can move up and down and rotate freely in cavity 63 but is prevented from falling out by cross pin 64. The lower end of element 62 is provided with an elongated cross member 65 which, when aligned with its long axis parallel to that of slot 60, will pass through this slot and in this position may be turned through 90° so as to engage the undersides of plates 59—59. The inside surface of cavity 63 is provided at the bottom with an inwardly projecting annular ridge formed with four upright cusps or peaks 67—67 spaced 90° from each other. Between each pair of peaks 67—67 the annular ridge is depressed to form a valley 68. Four such valleys 68 are thus found around the lower inside surface of cavity 63 and when cylindrical element 62 is not otherwise supported it must fall so that cross pin 64 lies within one of these four valleys 68. The upper end of cavity 63 is provided in similar manner with an annular ridge having four downwardly pointed peaks 70 separated by inverted valleys 71—71 spaced 90° apart. Valleys 71—71 at the upper end of chamber 63 are positioned very nearly opposite peaks 67—67 at the lower end of this chamber but are offset a few degrees, each valley 71 being offset from corresponding peak 67 in the same direction. When cylindrical member 62 is raised therefore, cross pin 64 is deflected downwardly extending peak 70 causing cylindrical element 62 to rotate about its long axis. When member 62 is raised until cross pin 64 occupies the bottom of an inverted valley 71, member 62 has been turned 45° from its original position. If this member is then allowed to fall, cross pin 64 is further deflected in the same direction by the peak or cusp 67 into the adjoining valley 68 which causes a further rotation of 45°. Each time cylindrical member 62 is raised and lowered, therefore, cross member 65 is turned through 90°.

The operation of my apparatus will now be described with reference to the present preferred embodiment which has been described in the foregoing paragraphs and is illustrated in the attached figures. It will be observed that tong member 38 can move only on the rollers 36—36 carried by pins 33—33 which pass through slot 39. The path of movement of tong member 38 is therefore determined by the shape of slot 39. This slot is conveniently made an arc of a circle and tong member 38 can move only lengthwise in the arcuate path determined by slot 39. The other tong members, being identical with tong member 38, also can move lengthwise only along arcuate paths. The pair of opposed tong members 38 and 40 therefore move from an open to a closed position along a path which is an arc of a circle. The length of each tong member and the length of the groove therein is adjusted so that the pair of tongs 38 and 40 in its open position spans the diameter of the circular arcuate path defined by slots 39 and 41, and closes completely in its closed position; that is to say, the lower ends of tong members 38 and 40 meet or overlap. The maximum overall width of tong pair 38 and 40 is therefore no greater when the tongs are fully open than it is when they are closed. It is this feature which makes my apparatus adaptable to loading articles into and out of confined spaces where side clearance is limited, and my apparatus requires no additional side clearance for opening.

Let it be assumed that my apparatus is in the position

shown in Figures 1 and 2, that is, with both pairs of tong members in the fully open position and latch mechanism 61 adapted to connect upright member 1 to lower cross member 23, as illustrated in Figure 8. In this position my apparatus can be moved about by a crane and positioned above a load of elongated articles to be lifted. Such articles must be supported by blocks or other means of a height sufficient to permit the lower ends of the tong elements of my apparatus to pass beneath the load, but this requirement must also be met for articles to be lifted by conventional sling means. My apparatus is lowered over the load with its open tong members straddling the load until the upper surface of the latter makes contact with the lower face of plate 24. Lower cross member 23 is then prevented from further descent by its contact with the load. Similarly, cylindrical member 62 of latch member 61 is likewise prevented from further descent, as it is supported by plate 24. If, therefore, element 1 and everything supported by it is allowed to descend further, cylindrical member 62 moves upwardly with respect to cavity 63 and is turned through an angle of about 45° when cross pin 64 is deflected by a face of downwardly projecting peak 70. If now element 1 is lifted slightly, tubular member 62 moves downwardly with respect to cavity 63 and is rotated an additional 45° as cross pin 64 is deflected by a sloping face of upwardly projecting peak 67. This rotation of 90° turns cross member 65 into the position shown in Figure 7 in which it is parallel with slot 60 and, as upward movement of element 1 continues, cross member 65 is withdrawn from slot 60, disconnecting lower cross member 23 from upright element 1. Upward movement of element 1 carries along with it upper cross member 14 including hanger elements 12—12 and 13—13. Hanger pair 12—12 transmits through link pairs 47—47 and 51—51 upward movement to the upper or pin ends of tong members 38 and 40 and causes these tong members to move through their arcuate path into the final closed position shown in Figure 3. In this position tong members 38 and 40, and, of course, tong members 42 and 44 as well, enclose the load. As upper cross member 14 moves away from lower cross member 23, upright projections 29 and 31 which are attached to lower cross member 23 act as guides so that cross members 14 and 23 remain parallel and aligned. When tong members 38 and 40 reach their closed position shown in Figure 3, the lower ends of links 47—47 and 51—51 bear against the rounded shoulders of lugs 25—25 and lug 28, preventing further movement of tong members 38 and 40 with respect to each other. The load enclosed by the four tong members is then lifted, its weight being transmitted by the four tong members through their associated connecting links and hangers to cross member 14 which in turn is carried by cross pieces 7 and 8 bolted to upright member 1.

When the load carried by my apparatus is to be set down, my apparatus is lowered until the load rests upon blocks or skids positioned to receive it. Lowering of my apparatus is then continued until the lower face of plate 24 again rests upon the upper surface of the load. The weight of descending upright element 1 and cross member 14 then causes tong elements 38 and 40 to move in their arcuate path to the open position shown in Figure 2. When latch mechanism 61 carried at the lower end of upright element 1 approaches cross member 23 closely enough, member 65 enters slot 60 and bottoms on the upper surface of plate 24. This brings about the operation of my latch mechanism 61 in the manner already described so as to connect upright member 1 with lower cross member 23. My apparatus can then be lifted clear of the load.

It will be observed that latch mechanism 61 carries no load other than the weight of lower cross member 23. Guide members 29 and 31 likewise carry no load, nor do pins 33—33 and bolts 20—20 and 21—21. It will also be observed that my tongs are of the self-locking type,

that is, the force exerted by the load acts upon my mechanism in such fashion as to force the tong members into their closed position. My tongs cannot be opened unless the load is otherwise supported. It will also be observed that my upper cross member 14 is constructed so that it is self-aligning with respect to lower cross member 23. This is brought about by the construction of the hangers 12—12 and 13—13 which rest on cross members 10 and 11 and against upright guide members 29 and 31 respectively, but are free to move laterally to a certain degree.

It is necessary to provide the vertical slots 3 and 4 previously mentioned in upright member 1, which in turn permit a certain amount of movement of upper cross member 14 with respect to upright member 1, to permit my apparatus to operate as above described when a load of maximum height considerably less than the inner diameter of the tong circle is being unloaded on the ground or low blocks. In such case the tong members strike the ground or floor before plate 24 comes to rest on top of the load, and must push cross member 14 upwards with respect to upright 1 to permit plate 24 to reach its lowest position. This lowest position with respect to the ends of the tong members is fixed by the geometry of the device, and places a limit on the minimum height of load which can be handled by my apparatus if the load is not properly blocked.

I claim:

1. Article lifting apparatus comprising an upright load-transmitting member, an upper cross member supported thereon and movable vertically thereon, a lower cross member movable vertically with respect to the upper cross member and with respect to the upright load-transmitting member, means slidably connecting upper and lower cross members so as to maintain alignment thereof, a pair of opposed elongated arcuate tong members, means slidably attaching the tong members to the lower cross member for movement lengthwise of the tong members in an arcuate path from a closed position in which their lower ends assume a load-enclosing relation to an open position in which the lower ends assume a load-straddling relation, separate load-transmitting means pivotally connected between the upper end of each tong member and the upper cross member, and means detachably connecting the upright load-transmitting member to the lower cross member when the tong members are in their open position but not in their closed position.

2. Article lifting apparatus of claim 1 in which the means slidably attaching the tong members to the lower cross member comprise a pair of spaced pins fixed to the

50 lower cross member parallel thereto and an arcuate slot in each tong member extending lengthwise thereof from a point near the upper end thereof, through which both pins pass.

5. Article lifting apparatus of claim 1 in which the means slidably connecting upper and lower cross members so as to maintain alignment thereof comprises a slot in the upper cross member and an upright member affixed to the lower cross member and passing through the slot in the upper cross member in slidable relation therewith.

6. Article lifting apparatus of claim 2 in which the lower cross member is provided with lugs extending beyond the pins and adapted to transmit load from the arcuate tong members to the load-transmitting means pivotally connected between the upper ends of the tong members and the upper cross member.

7. Article lifting apparatus of claim 1 in which the load-transmitting means pivotally connected between the upper ends of the tong members and the upper cross member comprise a hanger supported by the upper cross member and slidably thereon lengthwise thereof and a pair of links pivotally connected between the hanger and the upper end of each tong member respectively.

8. Article lifting apparatus of claim 1 in which the means slidably connecting upper and lower cross members so as to maintain alignment thereof comprise a hanger supported by the upper cross member and slidably thereon lengthwise thereof, a vertical slot in the hanger and an upright member affixed to the lower cross member and passing through the slot in the hanger in slidable relation therewith.
